(57) **CLAIM**

The ornamental design for a fishing cart, as shown and described.

DESCRIPTION

FIG. 1 is a front perspective view of a fishing cart showing our new design;

FIG. 2 is a left elevation view thereof;

FIG. 3 is a right elevation view thereof;

FIG. 4 is a front elevation view thereof;

FIG. 5 is a top plan view thereof;

FIG. 6 is a rear elevation view thereof; and,

FIG. 7 is a bottom plan view thereof.

The broken lines shown in FIG. 1 are included for the purpose of illustrating environment and forms no part of the claimed design.
